UNITED STATES PATENT OFFICE.

LYMAN W. WELCH, OF GRAND RAPIDS, MICHIGAN.

GARMENT-HANGER.

1,196,916.

Specification of Letters Patent. Patented Sept. 5, 1916.

Application filed March 8, 1915. Serial No. 12,857.

To all whom it may concern:

Be it known that I, LYMAN W. WELCH, citizen of the United States, residing at Grand Rapids, Kent county, Michigan, have invented certain new and useful Improvements in Garment-Hangers, of which the following is a specification.

This invention relates to improvements in garment hangers.

10 It relates to that style of garment hangers which are adapted to coats and trousers or jackets and skirts, and consists of a coat or jacket hanger with the cross bar structure beneath.

15 The objects of this invention are to provide such a structure with an improved cross bar means for clamping and carrying trousers or for similar purposes.

20 Further objects, and objects relating to details, will appear from the detailed description to follow.

I accomplish the objects of my invention by the devices and means described in the following specification.

25 The invention is clearly defined and pointed out in the claims.

A structure which is a preferred embodiment of my invention is illustrated in the accompanying drawing, forming a part of 80 this specification, in which:

Figure I is a perspective view of a garment hanger embodying the features of my invention. Fig. II is an enlarged detail longitudinal sectional view through the supporting bar and the ends of the coat or jacket hanger arms, showing the methods of attaching the supporting bar and details of arrangement and form. Fig. III is an enlarged detail cross-sectional view on line 85 3-3 of Fig. II, showing the relation of these parts when closed. Fig. IV is an enlarged detail transverse sectional view on line 4-4 of Fig. II, showing the relations of the swinging bar to the fixed bar and the 40 spring catch device at that point. Fig. V is a detail plan view of the end of the swinging bar showing the notching of the same.

In the drawing sectional views are taken looking in the direction of the little arrows 50 at the ends of the section lines and similar numerals of reference refer to similar parts throughout the several views.

Considering the numerals of reference, the laterally projecting arms 1, 1 of the 55 coat hanger are secured together by a metal plate 2 at the center within which is secured

the usual supporting hook 3 by which the garment hanger is suspended. Disposed within the lower ends of the laterally projecting arms 1, 1 is a cross piece 4 which is 60 semi-circular in cross section at the center and flattened toward the ends, which conforms to the underside of the arms 1, 1 at 5 and is secured in place by the screw 6. Toward one end this bar 4 is looped downwardly at 7 with an upwardly projecting dented or bumped portion 8, as clearly seen in Figs. II and IV. The loop portion 7 is notched about half way across at 9, as clearly appears in Fig. III. A swinging 70 bar 10, which is semi-circular in cross section with the curved side up, is pivoted at 11 to the flat portion of the supporting bar 4 at one end and is notched at 12 at the point of engagement with the notch 9 in 75 the loop 7 at the opposite end, and the semi-circular free end of the bar 10 snaps over the upwardly bumped part 8, thereby securing the same yielding in place for the support of trousers or skirts disposed upon 80 the bar 10 before the same is closed.

I have shown the engaging portions of the bars 4 and 10 as semi-circular in cross section, as that secures rigidity and the best action, but desire to state that these bars 85 may be of any other appropriate form at this point as, for instance, flat.

In the structure that I have produced, the support for the bar 10 is effectively accomplished without the addition of parts to the 90 bar 4, and a very simple and economical device effectively retained in closed position by the snap means is thus secured.

I desire to claim the structure specifically as well as broadly as indicated in the 95 appended claims.

Having thus described my invention, what I claim as new and desire to secure by Letters Patent, is:

1. In a garment hanger, the combination 100 of a suitable coat hanger with laterally projecting arms, a supporting cross bar of U-shaped cross section secured to the underside of said arms and having a downwardly projecting loop toward one end of the same, 105 with a lateral notch therein, and with a bumped-up portion to form a yielding catch member, a U-shaped straight bar with curved surface upward pivoted at one end beneath the supporting bar, and notched to 110 engage the downwardly projecting loop portion and adapted to engage over the

- bumped-up catch member of said upper bar when in closed position, all coacting substantially as described for the purpose specified.
- 5 2. In a garment hanger, the combination of a suitable coat hanger with laterally projecting arms, a supporting cross bar of U-shaped cross section secured to the under side of said arms and having a downwardly
- 10 projecting loop toward one end of the same, with a lateral notch therein, a U-shaped straight bar with curved surface upward pivoted at one end beneath the supporting bar, and notched to engage the downwardly
- 15 projecting loop portion, all coacting substantially as described for the purpose specified.
3. In a garment hanger, the combination of a suitable coat hanger with laterally projecting arms, a supporting cross bar with a lateral notch toward one end, secured to the under side of said arms, a bar disposed on a vertical pivot at one end beneath the said supporting bar and notched at its opposite end to engage and coact with the notch in said supporting bar.

In witness whereof, I have hereunto set my hand and seal in the presence of two witnesses.

LYMAN W. WELCH. [L. s.]

Witnesses:
